UNITED STATES PATENT OFFICE.

LOUIS STEINBERGER, OF NEW YORK, N. Y.

STRAIN-INSULATOR.

1,011,652.

Specification of Letters Patent. Patented Dec. 12, 1911.

Application filed May 25, 1910. Serial No. 563,293.

To all whom it may concern:

Be it known that I, LOUIS STEINBERGER, a citizen of the United States, and a resident of the city of New York, borough of Brooklyn, in the county of Kings and State of New York, have invented a new and Improved Strain-Insulator, of which the following is a full, clear, and exact description.

My invention relates to insulators for general use, and more particularly to a type of strain insulator suitable for service in connection with wiring, and subjected to comparatively high mechanical and electrical stress.

More specifically stated, my invention embodies a metallic member provided with an open central portion and with annular ends beveled internally and fitted with insulating sleeves of frusto-conical form, and strain members provided with frusto-conical heads fitted within these sleeves and adapted to be pulled in opposite directions; a mass of insulating material enveloping the central metallic member, the sleeves, and part of the strain members.

Reference is to be had to the accompanying drawings forming a part of this specification, in which similar characters of reference indicate corresponding parts in all the figures.

Figure 1 is a central section through my improved strain insulator showing the relative arrangement of the central metallic link, the frusto-conical sleeves mounted therein, the metallic bolts and their accompanying parts extending into the sleeves, and a mass of insulating material provided externally with corrugations and molded around the entire structure except the outer ends of the bolts; Fig. 2 is a vertical cross section upon the line 2—2 of Fig. 1 looking in the direction of the arrow, and showing in cross section the mass of insulating material and also the central bars connecting the rings of the link together; Fig. 3 is a central cross section through the link, provided at its ends with rings and frusto-conical sleeves, this view further showing the metallic members mounted within the sleeves; Fig. 4 is a perspective showing the link complete, including the rings connected together by the central bars; and Fig. 5 is a perspective of one of the frusto-conical sleeves.

Two rings 6 of massive construction, are made of metal and are each provided inter-

nally with a beveled or tapered surface 7, as will be understood from Figs. 3 and 4. Such being the case, each ring 6 is thicker and more massive toward its ends than toward the center. The rings 6 are connected together by center bars 8 integral therewith, each of these center bars having a cross section of the kind indicated in Fig. 2.

Insulating sleeves 9, 10, of frusto-conical form are fitted into the rings 6, in such manner that the small ends of the sleeves extend in opposite directions. A nut 11, of frusto-conical form, is provided with a smooth exterior that fits neatly against the inner surface of the sleeve 9. A bolt 12 is provided with an eye 13, and is further provided with a shoulder 14, and with a threaded portion 15, all of these parts being integral. The nut 11 is threaded internally and fitted upon the threaded portion 15 of the bolt 12. When screwed firmly into position, the nut 11 locks tightly against the shoulder 14, so as to be held firmly in position relatively to the bolt. The nut 11 is provided with holes 16 and the threaded portion 15 is provided with a slot 17. The holes 16 are used to facilitate the application of a wrench, and also serve as anchorage. The slot 17 is also for the purpose of affording anchorage for the insulating material with which the link is afterward fitted, as hereinafter described.

A frusto-conical head 18, provided with a smooth exterior, fits neatly against the inner surface of the sleeve 10, and is provided with holes 19 and with a stem 20 and a clevis 21, the latter and the stem 20 being integral with the head 18. The clevis is provided with holes 22, the head 18, stem 20, and clevis 21 together constituting a strain member. Similarly the nut 11 and bolt 12 together constitute the opposite strain member.

At 23 is shown a mass of insulating material, which in a plastic state is molded into and around the link so as to envelop it together with all parts connected with it, except a portion of the bolt 12, its eye 13, and the stem 20 with its clevis 21, as will be understood from Fig. 1.

In assembling the parts above described, the entire link shown in Fig. 4 is produced in any suitable manner, and the sleeves 9, 10, are let into it from the center; next the nut 11 is passed into the sleeve 9 from the center; the bolt 12 may be connected with

the nut 11 as the latter is inserted, or afterward if desired. The head 18 is next inserted from the center, the clevis 21 being first passed through the sleeve 10, and the 5 parts being in this position the nut 11 and the head 18 are drawn in opposite directions so as to fit tightly in position, the parts now assuming the form indicated in Fig. 3. The plastic material is next filled into and 10 around the link, and provided with corrugations 24, as indicated in Figs. 1 and 2.

In some instances I may deem it proper not to use the plastic material 23, and in such event the strain insulator as finished, 15 will appear as indicated in Fig. 3. When used in this form the parts may be readily assembled or disassembled at will, whereas if the insulating material be applied as indicated in Fig. 1, the structure becomes to 20 all intents and purposes practically integral therewith, and no part can readily change its position relatively to any other part.

I do not limit myself to the use of any particular insulating material for the construction above described, but prefer in practice to employ the material well known in the art as "electrose". Neither do I limit myself to the particular combination shown nor to the exact form of any or all 30 of the parts above shown or described, as variations may be made by those skilled in the art without departing from the spirit or scope of my invention.

Having thus described my invention, I 35 claim as new and desire to secure by Letters Patent:

1. A strain insulator comprising a link provided with annular portions having openings therein of a general tapering 40 form, said annular portions being exteriorly of uniform diameter, sleeves of insulating material mounted within said openings, and strain members provided with portions ex-

tending into said sleeves and fitting the same.

2. A strain insulator comprising a pair 45 of rings connected together by center bars integral therewith, said rings being provided with openings tapering in diameter, each ring being thicker where bounded by the outermost portions of said openings, sleeves of insulating material mounted within said openings and each having generally a frusto-conical form, and strain members extending into said sleeves and provided with 50 portions of frusto-conical form engaging said sleeves.

3. A strain insulator comprising a pair 55 of metallic rings connected together by center bars integral therewith, one of said rings being more massive at its outer end than toward its center, and having an opening of tapering diameter, a frusto-conical sleeve mounted within said opening, a strain member provided with a portion of frusto- 60 conical form fitted into said sleeve, and mechanism for engaging the other of said rings.

4. A strain insulator comprising a body 65 portion of metal provided with an opening, a sleeve of insulating material mounted within said opening, a head disposed within said sleeve, a stem extending from said head, a clevis upon said stem, said clevis being of sufficiently small diameter to pass 70 through said sleeve, and mechanism for supporting the opposite end of said body portion of metal.

In testimony whereof I have signed my name to this specification in the presence 75 of two subscribing witnesses.

LOUIS STEINBERGER.
